UNITED STATES PATENT OFFICE.

HARRY J. WARTHEN, OF WASHINGTON, DISTRICT OF COLUMBIA.

ELECTRIC SIGNAL SYSTEM FOR RAILWAYS.

1,090,357.

Specification of Letters Patent. Patented Mar. 17, 1914.

Application filed June 16, 1910. Serial No. 567,300.

To all whom it may concern:

Be it known that I, HARRY J. WARTHEN, a citizen of the United States, residing in the city of Washington, District of Columbia, have invented an Electric Signal System for Railways, of which the following is a full and complete specification.

This invention is an electric signal system for railways, and relates more especially to a system of electrically-operated devices for the purpose of automatically controlling the operation of trains.

The primary object of the invention is to provide a system of electrically-controlled devices which are maintained in normal condition by closed electric circuits, and will operate by gravity to effect an application of the air-brakes to a train when the electric circuits are broken or shunted from any cause.

In the present instance the system comprises electric circuits for the sections or blocks of a railway track, herein termed "track-circuits", an electric circuit in the cab of a locomotive or motor-car, herein termed "cab-circuit", in connection with relays in the track-circuits, supplemental electric connections or conductors, including armatures of the relays, and coöperating with the cab-circuit, and air-brake control devices held in normal position by the closed cab-circuit and operated by gravity to effect an application of the air-brakes when the cab-circuit is broken; all as hereinafter fully described and specifically set forth in the appended claims.

In the accompanying drawings, forming a part of this specification:—Figure 1 is a diagram view illustrating the complete system; Fig. 2 is a view illustrating that part of the system which is carried by the locomotive, or cab, and including the trolley device. Fig. 3 is a sectional view through the trolley device. Fig. 4 is a detail view of the armatures and connecting-plate employed in connection with the relays of the track-circuits.

Like numerals of reference indicate like parts in all the figures of the drawings.

In carrying out my invention the railway is divided into blocks or sections, each provided with a "station", and though I have shown in the present instance only a small number of blocks and stations it will be

understood, of course, that the number will depend upon the length of the railway and the distance apart the stations are placed, and that in practice a considerable distance or length of track will intervene between stations, the distance being determined by traffic conditions in each particular case. The stations shown in the drawings are designated, for convenience of description, as A, B, C, D and E, respectively, and each block comprises that section of track at opposite sides of a station to a point intermediate the next station in either direction.

5 and 6 designate the track-rails, and in the present instance these are adapted primarily to form the electric conductors for the track-circuits, one of these rails, as 5, being disconnected, electrically, at each station by means of an insulating-block 7, and also electrically disconnected at a point intermediate the stations by insulating-blocks 8. The other rail, 6, is continuous to form a common conductor for both the track-circuits and the supplemental connections or conductors which coöperate with the cab-circuit, as hereinafter explained.

At each station are located two relays, 9 and 10, of conventional form, independently connected to the track-rails 5 and 6, respectively; the relay 9 by wire 11 to rail 6 and by wire 12 to rail 5 at one side of the insulating-joint 7; while relay 10 is connected by wire 13 to rail 6 and by wire 14 to rail-section 5 at the other side of the insulating-joint 7. The relays 9 and 10 are energized by batteries 15, which are so connected that the current will have to pass through a length of the track to said relays, and in the present instance the connections are such that the two relays at adjacent stations and at opposite ends of the same block are connected in a single series circuit. To this end each battery 15 is connected around the insulating-joint 8 to the track-rail sections 5, 5, so that current will pass from one side of the battery through rail-section 5, wire 100 12, to and through relay 9, wire 11, back along rail 6, wire 13 at the other end of the block, relay 10, wire 14, and return along the other rail-section 5 to the other side of the battery, thus maintaining both rails of the track in a permanently closed series circuit.

Each pair of relays 9 and 10 is provided with independent armatures 16 and 17, re-

spectively, which when the relays are energized are electrically connected by a conductor-plate 18, these connections—the armatures and plate—forming part of the supplemental conductors which coöperate with the cab-circuit, hereinafter described. To this end armature 16 is connected by wire 19 to track-rail 6, and armature 17 by wires 20 and 21 to ramp-rails in certain blocks in both directions from the station at which the pair of relays are located—in the present instance the blocks at each side of the block controlled by said station. Therefore, wire 20 from each station of a block is connected to a ramp-rail 22 in the next block in one direction, and wire 21 to a ramp-rail 23 in the next block in the other direction, the last mentioned ramp-rail, or wire 21 leading thereto, being electrically connected to a supplemental ramp-rail, as 24, located in the same block with ramp-rail 23 at a distance therefrom; as for instance, armature 17 in block C is connected by wire 20 to ramp-rail 22 in block B, and by the wire 21 to the connected ramp-rails 23—24 in block D. The armature 17 is provided with two conducting-elements, 17^a and 17^b, (see Fig. 4), to which the wires 20 and 21 are connected, respectively, said conducting-elements being insulated from each other, as shown, and similarly the conductor-plate 18 is provided with separate conducting-elements through which the contact-points 18^a pass. In this manner, as will be apparent, the wires 20 and 21 have independent connections, so that the current cannot pass from one to the other, but may pass from either or both through the common conductor 16 to wire 19 when both relays 9 and 10 are energized, and when either relay is deënergized the current is broken.

One side of the battery 25 of the cab circuit is connected by a wire 26 to a trolley, as 27, on the locomotive, or cab, which engages the ramp-rails 22 and 23—24, while the other side of said battery is connected by a wire 28 to the frame of the locomotive so as to electrically connect with the rail 6, as indicated in Fig. 1, certain devices, as a solenoid 29 and signal-lamps 30 and 31 being included in the circuit, for the purposes hereinafter explained. The cab-circuit when closed, therefore, is from one side of the battery 25 by wire 26 to trolley 27, ramp-rail 22, or 23, wire 20, or 21, through armatures of relays 9 and 10, wire 19, track-rail 6, engine-frame, and return by wire 28 to the other side of the battery. The cab-circuit may be broken by the deënergization of either relay 9 or 10 through the breaking or shunting of a track-circuit, as hereinafter explained, or when the trolley 27 leaves the ramp-rail, this latter condition being prevented, however, by a particular form of trolley-device hereinafter described.

In the present instance the solenoid 29 when energized by a closed cab-circuit holds the plug 32 of a valve 33, so that air from the main reservoir 34 of the air-brake system may pass into a cylinder 35 and maintain the piston 36 therein in its uppermost position to supply air from pipe 37 leading from the reservoir 36 through passage 38 in said piston to a pipe 39 supplying the train-line of the air-brake system; thus permitting of the normal operation of the air-brake mechanism. When the parts are in this, the normal position, the white signal-lamp 30, which is wired around the solenoid, will be lighted. When the cab-circuit is broken the deënergization of the solenoid will cause the staff 40 thereof to drop by gravity, thus turning the plug 32 of valve 33 so that the cavity 41 therein will connect the cylinder 35 with the exhaust-port 42 in the valve, exhausting cylinder 35, by gravity which permits piston 36 to drop and cut off the supply of air-pressure to the train-pipe; the pressure remaining in the train-pipe being then exhausted through a cavity 43 in the piston and an exhaust-port 44 in the cylinder, thus causing the air-brakes to be automatically applied, as will be obvious. When the solenoid is deënergized the white signal-lamp 30 is extinguished, and in order to show a red-light, or danger-signal simultaneously with the deënergization of the solenoid, the lamp 31, showing a red light, is wired to both sides of the battery 25, with an interposed make and break device, which latter is operated by the solenoid. To this end, therefore, a wire from one side of the battery 25 and lamp 31 is connected to one of a pair of spaced apart contact-points 45, 45, the other of which latter is connected to the other side of the battery, as shown; the contact-points being connected to complete the lamp circuit by a plate 46 carried by the staff of the solenoid and adapted to rest upon said points when the solenoid is deënergized.

To assist in the operation of the valve 33 by the gravity of the staff of the solenoid, when the latter is deënergized, the staff 40 is provided with a weight 40^a; and for the purpose of lifting the weighted staff to restore a normal condition of the air-brake control devices and thereby permit the train or locomotive to proceed, the staff 40 is connected to a piston 47 in a cylinder 48, and the space in said cylinder below the piston is connected by pipe 49 to the upper part of a second cylinder, 50, having a piston 51 curved at its lower end, for the engagement of an operating-lever 52; whereby when the piston 51 is forced upward the air which is compressed in the upper part of cylinder 50 will pass through pipe 49 to cylinder 48 and lift the piston 47 and staff carried thereby. The lever 52 may be, and preferably is, operated by the engineer's starting-lever, 54, 130

through the connecting-rod 53, and the connection with the starting lever is such that the piston 51 is raised only when the starting-lever is reversed, to back the train. In this manner, as will be seen, the train can be backed but cannot proceed forward until the solenoid is energized by the closing of the cab-circuit.

Of course by employing a continuous third-rail an ordinary form of trolley could be used for connecting the battery in the cab of a moving locomotive to the supplemental conductors which include the armatures of the relays, but inasmuch as I propose using the comparatively short ramp-rails 22 and 23—24, it is necessary to employ a particular form of trolley device which will maintain the cab-circuit closed after passing a ramp-rail, provided the electric connections which include said ramp-rail are closed when the train passes the same. The particular form of trolley device which I use is illustrated in Figs. 2 and 3 of the drawings, and consists of a wheel 55, loosely mounted on a suitably supported shaft 56 and carrying the oppositely-projecting trolley-arms 57, so that said wheel will be turned when either trolley-arm is depressed. Mounted on the shaft 56, alongside of the wheel 55 is a magnet 58, adapted to attract and hold to said wheel so as to turn therewith, for the purpose hereinafter explained. The rotatable magnet is provided with a pair of switch-blades 59, to which the wire 26 from the cab-battery 25 is connected, said switch-blades being adapted to engage a suitably-supported switch-blade 60, which latter is connected by a wire 61 to the wire 28 that leads to the other side of the cab-battery through the solenoid, whereby said solenoid is energized when the switch 59—60 is closed. The electrical connections for the magnet consist of a wire 62 connecting with the wire 61, and a wire 63 connecting with the wire 28 between the solenoid and battery 25, whereby when the solenoid is energized by said cab-battery and its connections the magnet will also be energized, and, conversely, when the connections to the battery 25 are broken the magnet is deenergized, for the purpose hereinafter explained. The trolley-arms are suitably guided by standards 64, and may be returned to a normal horizontal position by means of suitable springs, as will be obvious. This trolley-device may be located at any convenient place on the locomotive.

It will be understood, of course, that in practice only one trolley-arm operates on the ramp-rail, the oppositely disposed arm being employed so that either one will engage the ramp-rail whether the locomotive is being run forward or backward.

The operation of the system is illustrated, in Fig. 1 of the drawings, wherein a train

occupying block B, in the present instance to the right of the insulating-point 7, has deenergized or cut out relay 9 of said station B by shunting the circuit from battery 15 between stations B and C through the wheels and axle of the train from rail-section 5 to rail 6, current from said battery then passing by rail 6 to wire 13 of station C, relay 10, wire 14, and rail-section 5 to other side of battery, and as armature 16 of station B has dropped by reason of the deenergization of its relay 9 the connection of wires 20 and 21, armature 17, conductor-plate 18, said armature 16, wire 19 to rail 6, is broken at this point (armature 16), wire 21 in this instance extending to ramp-rail 23 at station C, as shown, so as to signal a train when it arrives at this ramp-rail. Under these conditions, a train entering station C from the right has its trolley depressed by the ramp-rail 23, thus opening the switch 59—60 in the cab of the locomotive of said train, so that the cab-circuit must then be completed by wire 26, trolley 27, ramp-rail 23, wire 21, armature 17 of station B, conductor-plate 18, armature 16, wire 19, common rail 6, locomotive engine-frame, wire 28, through solenoid to the other side of the cab-battery; but armature 16 at station B having dropped, by reason of train occupying block B, as hereinbefore stated, the cab circuit is broken and the solenoid in the engine-cab of train occupying station C is deenergized. This connects the danger-signal or lamp 31 in circuit with battery 25, and also operates the valve 33 to automatically apply the brakes to the train, in the manner as hereinbefore described; simultaneously magnet 58 is demagnetized so that should the locomotive proceed beyond ramp-rail 23 wheel 55 being thus disconnected from said magnet would return alone, leaving the magnet in the position shown in Fig. 2 of the drawings, with the switch 59—60 broken. The cab circuit would thus remain broken. However, the train can be backed to bring the trolley on to the ramp-rail again by reversing the engineer's operating-lever 54, which would restore or lift the staff of the solenoid and open the valve 33, the pressure from the reservoir then lifting piston 36 to admit air-pressure from said reservoir into the train-pipe connection 39; but should the engineer attempt to again proceed forward before reaching the ramp-rail the forward movement of the operating-lever would release the solenoid staff and again automatically apply the brakes; or should the engineer attempt to start the train forward after reaching the ramp-rail and before block B is cleared the attempt would be unsuccessful on account of the cab circuit being broken by armature 16 of station B, the switch 59—60 being still open. On the other hand, when block B is cleared 130

by the train therein passing into block A, armature 16 of station B is restored and the circuit through ramp-rail 23 of station C to train occupying latter station is also restored, energizing solenoid 29, extinguishing red-lamp 31, lighting white-lamp 30, and energizing magnet 58. The engineer may then move his train forward, and when the trolley leaves the ramp-rail the magnet 55 being held to wheel 55 will move with the latter and close the switch 59-60, thus maintaining the cab-circuit through the cab connections until the train arrives at the next ramp-rail. It will be understood that the connection of the supplemental conductors at station B, by armatures 16 and 17, will be broken as long as the train is in block B, for when the train moving from the right end of the block passes insulating-joint 7 of said station B relay 10 is cut out, and armature 17 at station B drops simultaneously with the restoration of armature 16, and the dropping of either armature breaks the connection at this point. It will be noted, also, that the train occupying block C deenergizes relay 9 in said station so that armature 16 thereof will not only establish a danger condition in block D in the rear by wire 21 to ramp-rails 23-24 in said latter block, but will also establish a signal condition at the farther end of station B in front by wire 20 to ramp-rail 22, so that the engineer of the train ahead will become aware of the fact that a train is following in station C as he passes over said ramp-rail. Ramp-rail 22 is also for the purpose of preventing head-on collisions, as will be obvious.

The system as shown and described is applicable to single-track railways, on which trains move in both directions and on which it is desirable to establish warning signal condition in both directions from the point of danger. It will be perfectly obvious, however, that my invention can, with slight modifications, be employed to equal advantage on double-track roads where the traffic on each track is in one direction only, as shown in drawing and where, as a general thing, it is only necessary to provide against rear end collisions.

While I have used the word battery throughout the specifications it will be understood, of course, that I mean to include primary or secondary batteries, generators, or other suitable source of current.

In the present instance I have specified that the trolley device is located on the cab of the locomotive, requiring, therefore, that the ramp-rails be in elevated position alongside of the track, but it will be understood, that the trolley may in some instances be placed at some point on the lower part of the locomotive, and the ramp-rails located 65 on the ground.

Furthermore, though I have described the deenergization of the relays of the track-circuits to establish a danger condition as effected by the passing of a train into each block, it will be readily apparent that the same danger condition will result should either one of the track-rails 5 and 6 of a block become displaced through any cause, for instance by a wash-out, broken rail-connection, etc. 75

Having thus described my invention, I claim:

1. A system for controlling the operation of railway trains, comprising a railway divided into sections or blocks each having a pair of track-rails one continuous and the other in two sections for each block insulated from each other and from like track-rail sections of the adjoining blocks in both directions, batteries connected each to a track-rail section of one block and adjoining track-rail section of the next block, relays arranged in pairs for each block and each connected by one pole to one of the two track-rail sections of that block, respectively, and by the other pole to the continuous track-rail forming a closed track-circuit including relays of adjoining blocks and both track-rails in a single series circuit, a contact-piece for connecting the armatures of each pair of relays when said armatures are attracted, ramp-rails each connected to one of the armatures, of a pair of relays, and connections between the companion armature and continuous track-rail; together with an electric circuit on the cab of a locomotive, and means for connecting said cab-circuit to include the aforesaid ramp-rails, armatures and connections, substantially as shown and described. 100

2. A system for controlling the operation of railway trains, comprising a railway divided into sections or blocks each having ramp-rails and a pair of track-rails one of which latter is continuous and the other in two sections for each block insulated from each other and from like track-rail sections of the adjoining blocks in both directions, batteries connected each to a track-rail section of one block and adjoining track-rail section of the next block, relays arranged in pairs for each block and each connected by one pole to one of the two track-rail sections of each block, respectively, and by the other pole to the continuous track-rail forming a closed track-circuit including relays of adjoining blocks and both track-rails in a single series circuit, one of the relays of each station having two armatures insulated from each other, ramp-rails at a distance 125 from said armatures in opposite directions and connected thereto respectively, a companion armature connected to the continuous track-rail, and a contact-piece for connecting said armatures when attracted to 130

gether with an electric circuit on the cab of a locomotive, gravity-operated devices controlled by said cab-circuit, and means for connecting the cab-circuit to include the 5 ramp-rails, armatures and connections along the railway-track, substantially as shown and described.

In testimony whereof I have signed my name to this specification in the presence of two subscribing witnesses.

HARRY J. WARTHEN.
